UNITED STATES PATENT OFFICE.

DELBERT F. DUNHAM, OF LOS ANGELES, CALIFORNIA.

VALVE-GRINDER.

1,342,875.

Specification of Letters Patent. Patented June 1, 1920.

Application filed March 24, 1919. Serial No. 286,166.

To all whom it may concern:

Be it known that I, DELBERT F. DUNHAM, a citizen of the United States, and a resident of Los Angeles, in the county of Los Angeles and State of California, have invented new and useful Improvements in Valve-Grinders, of which the following is a specification.

My invention relates to and has for a primary object the provision of an effective valve grinding mechanism capable of operation on a work bench or in any convenient place where power may be applied to the grinder by means of which disk valves, such as are used in internal combustion engines may be ground.

It is also an object of this invention to provide in connection with the usual grinder head, upon which are mounted a grinding wheel and a pulley by means of which the wheel may be rotated, a universally adjustable valve supporting mechanism for holding the valves in position relative to the grinder, the valve supporting means comprising a graduated table pivotally supported on the base of the grinder head and having an axis centrally positioned relative to the grinding wheel, and a carriage mounted upon said table and adjustable in a horizontal plane relative thereto, whereby the valve supported on the carriage for a grinding operation may be adjusted at a suitable angle relative to the face of the grinder.

A further object is to provide on the valve supporting carriage, a longitudinal adjustable valve holder for adjusting the position of the valve, so that the periphery of the valve to be ground may be moved relative to the face of the grinder.

A further object is to provide improved means for clamping the valve in position on the holder. Other objects may appear as the description progresses.

I have illustrated in the accompanying drawings forming a part of this application, one practical embodiment of this invention showing a novel arrangement of parts and features which I believe to be new in the art and which will be described in detail in the specification hereinafter following:

In said drawings:

Figure 1 is a plan of my valve grinding mechanism;

Fig. 2 is a side elevation thereof;

Fig. 3 is an end elevation of the same, partly in section;

Fig. 4 is a side elevation of the valve supporting carriage;

Fig. 5 is an end view of the valve holder; 60

Fig. 6 is a transverse section of the grinding head;

Fig. 7 is a section of the carriage on line 7—7 of Fig. 4;

Fig. 8 is a section of the same on line 65 8—8 of Fig. 4;

Fig. 9 is a longitudinal section of the valve holder showing the means of clamping the valve in position on the holder; 70

Similar characters of reference are employed in the specification and in the several views of the drawings for indicating the same and like parts.

A form of grinder head adapted for use in connection with my other improvements consists of a base, or standard 1, having spaced bearings 2, 2, at the top thereof in which a shaft 3 is rotatably held and on which shaft is a pulley 4, positioned between the bearings 2, 2, and adapted to be driven by means of a belt 5, connected with any suitable drive shaft, and a grinder wheel 6 on one end of said shaft which is removably held by means of the usual plates 7, 7. 75

On the base 8, of the standard 1, I provide a lug 9, which is positioned in the vertical plane of the grinder wheel 6, and is adapted to hold a stud 10, on one end of which stud is pivotally mounted a swinging standard 11, the stud 10 having a hexagon head 12 80 and a nut 13 on the other end by means of which the standard 11 may be secured firmly on the lug 9. 85

Standard 11 has a circular flange 14, formed integral therewith at the top and said flange may be provided with graduations, as at 15, on the periphery thereof for indicating degrees. A carriage is provided for attachment to the flange 14, and includes a cast metal base 16, which has a circular portion 17 at one end adapted to correspond to and to be mounted upon the flange 14 and held adjustably thereon by means of a stud or cap screw 18, so that the carriage may be bodily adjusted in a horizontal plane on the flange 14 to a desired extent, the movement thereof being determined by means of the graduations on the flange relative to a single line, as shown on the periphery of the base portion 17. 100 105 110

The carriage base has an extended arm 19, with a pair of spaced bearings 20, 20, formed thereon for receiving a shaft 21, which parallels the arm 19, one side of said shaft being flattened as at 22, for the entire length thereof, and split caps 23, 23, being provided on the tops of the bearings 20, 20, which are attached to said bearings by means of screws 24, 24, by means of which 10 the shaft 21 may be clamped in the bearings against longitudinal and rotary movement during a valve grinding operation.

The forward end of shaft 21 carries an arm 25, which may be secured to the shaft 15 in any suitable manner so as not to turn thereon and said arm is extended upwardly, and the upper end thereof is substantially enlarged and split for a substantial distance and threaded to receive an adjusting screw 20 26 having a knurled head 27 by means of which the screw may be turned in the end of the arm. The upper end of the arm 25 may be adjusted as to its tension on the screw 26, by means of a screw 28, and the 25 center of said screw 26 is in the same horizontal plane as the axis of the grinder wheel 6.

Adjacent to each of the bearings 20, 20, and between the same, I provide an arm 29 30 on the shaft 21, which is held immovable on said shaft and in a true vertical position by means of set screws 30, engaging the flattened portion of the shaft, the upper ends of said arms having yokes 31 thereon, which 35 serve as rests for the valve stems 32. When a valve 33 is in operating position on the yokes, the stems 32 will rest in the yokes and the valve will occupy a position opposite the grinder wheel 6 and between the arm 25 and 40 the adjacent yoke arm 29.

The valve 33 may be clamped firmly in position by means of the adjusting screw 26, the inner end of which screw is provided with a swivel extension 34 having a ball and 45 socket connection 35 with said screw and a conical point 36 on the opposite extremity thereof adapted to seat in a depression in the valve. It will be obvious that as the screw 26 is tightened, the face of the valve 50 33 will be moved into closer contact with the face of the wheel 6, and thus the grinding of the valve may be effectively regulated. The swivel 34 prevents the loosening of the screw 26 when the valve 33 is rotated. A 55 crank 37 may be provided on the outer end of the valve stem for turning the valve during the grinding operation. A flat spring 38 attached at its lower end 3^a around the shaft 21 and having its upper end resting 60 upon the valve stem to hold the stem resiliently in their supporting yokes.

It will be understood that the normal position of the valve 33 and the flange 14, is in alignment with the center of the face of the 65 grinder wheel and that the valve may be

moved over the face of the wheel by moving the carriage bodily about the axis of the standard 11, on the base of the grinder head. Such movement of the valve may in some cases facilitate the grinding of the valve, and 70 will also tend to prevent the wear of the wheel 6 unevenly over the face thereof. The turning of the valve by means of the crank on the stem thereof, will also facilitate the grinding of the valve, and the carriage being moved bodily about its vertical axis on the flange 14, the securing screw being first loosened, will facilitate the insertion and removal of the valve from the carriage.

It will be seen from the foregoing description that my invention consists broadly in the provision of a grinding head having a bodily adjustable carriage for supporting the valve and valve stem in position for grinding, several adjustments being provided for facilitating the grinding operation, and I desire to claim broadly thereon.

What I claim is:

1. A valve grinding mechanism comprising a valve cutting element, a carriage for supporting a valve in position for cutting, a valve carried thereby, an adjusting screw for moving said valve longitudinally of said carriage, and a swivel on the end of said screw for engagement with said valve, whereby said valve may be held against the face of the grinding element.

2. A valve grinding mechanism comprising a grinding head; a grinding element thereon, a pivoted standard attached to said grinding head, a carriage pivotally held on said standard and adapted to be adjusted in a horizontal plane for positioning the object to be ground, a valve holder longitudinally adjustable on said carriage, a valve and stem being adapted to be rotatably held in said holder for contact with said grinding element, and a tension element carried on said carriage and adapted to press against said valve stem for yieldably holding said valve and stem in working position.

3. A universal valve grinding mechanism including a grinding element and a carriage adjustable relative thereto, a valve holder on said carriage having a longitudinally adjustable rod with yokes thereon for holding a valve to be ground, being adapted to hold a valve and stem, and means held on said rod and engaging said valve stem for resiliently holding said valve in position for grinding.

4. In a valve grinding mechanism having a rotary grinding element, a pivoted standard having a horizontal axis disposed at right angles to the axis of the grinding element, a carriage thereon having a vertical axis of adjustment, a rod slidable on said carriage and having a valve support thereon and supports also thereon and spaced apart

- for holding, a valve and stem thereon, a screw for adjusting the pressure of the valve against the grinding element, and a swivel on the end of said screw, whereby said valve may be rotated without loosening said screw.
5. A valve grinding mechanism comprising in combination with a grinding element and a valve holder adjustably mounted thereon, and adapted for supporting a valve, an adjusting screw on said holder for holding the valve in contact with the grinding
- 10

element, and a swivel on said screw for preventing the loosening of said screw when said valve is rotated.

Signed at Los Angeles, Los Angeles 15 county, California, this 8th day of March, 1919.

DELBERT F. DUNHAM.
